UNITED STATES PATENT OFFICE.

HENRY CARLISLE STEWART, OF PHILADELPHIA, PENNSYLVANIA, ASSIGNOR TO THE
WESTMORELAND CHEMICAL & COLOR COMPANY, OF PHILADELPHIA, PENNSYLVANIA, A CORPORATION OF PENNSYLVANIA.

METHOD OF MANUFACTURING IRON OXIDE.

Application filed May 3, 1923. Serial No. 636,436.

My invention relates to the method of manufacturing oxide of iron for use in the manufacture of pigments of various kinds. One method employed in the manufacture of 5 oxide of iron consists in the roasting or burning of ferrous sulphate or copperas ($FeSO_4 \cdot 7H_2O$) in suitable furnaces, preferably rotary kilns of a character similar to those employed in the manufacture of cement. In the process of burning the copperas gases of various kinds are given off which unless neutralized or eliminated before being discharged into the atmosphere are apt to result in injury to various 10 surrounding objects, such as vegetation, wearing apparel, etc. In addition to the gases of combustion which are discharged from the kiln may be mentioned also sulphurous oxide (SO_2) and sulphuric oxide (SO_3). The latter, if there happens to be a sufficient amount of moisture in the air, combines therewith to form sulphuric acid which may deposit upon surrounding objects of the 15 character above indicated and cause injury thereto.

One of the objects, therefore, of my invention is to provide new and novel means which may effect in a practical way the elimination of the deleterious gases, particularly sulphuric oxide, from the gases discharged 20 from the furnace or kiln so as to prevent the discharge of the same into the air from a smoke stack or other conduit for conveying the gases from the furnace or kiln.

A further object of my invention is to provide an improvement in the manner or method of introducing the copperas into the furnace or kiln wherein it is to be incinerated in such manner as to effect a more satisfactory and efficient incineration thereof.

A still further object of the invention is to effect removal from the gases discharged from the furnace any oxide of iron which may be carried thereby from the furnace or kiln.

Other objects and advantages of my invention will be pointed out in the detailed description thereof which follows or will be apparent from such description.

Although the method invented by me is not dependent upon any particular kind or construction of apparatus for its practice it is obvious that some form of apparatus must be employed in connection with the carrying

out of the same. In the accompanying drawing I have shown a view partially in side and partially in sectional elevation of a novel construction of apparatus employed in the carrying out of the method or process embodying my invention. An apparatus embodying the principle of construction as illustrated in the said drawing has been employed in actual operation and has been found to operate in an entirely satisfactory and efficient manner.

Referring to the drawing: 1 designates a rotary kiln of known construction supported in known manner and rotated in known manner by means, as indicated at 2. 3 designates an apparatus employing an underfeed stoker construction for supplying a flame through an opening at 4 by means of which the copperas supplied at the smaller upper end of the kiln is incinerated or burned so as to decompose the same and obtain at the lower end of the kiln the product desired; namely, ferric oxide (Fe_2O_3). For the purpose of supplying the copperas to the upper end portion of the kiln cylinder 1 I have provided a tube 10, the lower end of which terminates within the said cylinder adjacent its upper end. At its upper end the tube 10 is connected with a branch tube 11 into which a funnel-like hopper 12 opens and through which the copperas is supplied to the branch tube 11. For the purpose of driving the copperas forward through the tube 10 into the kiln cylinder 1 the branch tube 11 is extended beyond the point of connection of the hopper 12 thereto to an air blower or pump 13 which forces the air through the branch tube 11 and through the tube 10 to cause the said copperas to properly feed through the said tubes 11 and 10. In order to prevent the rapidly moving column of air which is discharged from the blower 13 from acting against the column of material flowing from the hopper 12 I have provided a baffle-plate or protecting plate 15 which extends partially over the lower open end of the connection of the hopper 12 to the branch tube 11.

In order to prevent the copperas from partially melting and caking in the lower end portion of the tube 10 I have surrounded such portion with a larger tube 17 of considerably greater diameter than the tube 10 so that a cylindrical space annular in cross-

section is formed between the said tube 10 and the tube 17. The latter tube is provided adjacent its upper end with openings 20, the presence of which allows air to enter into the space between the said tubes 10 and 17.

The forcing of the air from the air pump or blower 13 through the pipe 10 causes the copperas to be discharged from the lower 10 end of the latter pipe forwardly into the kiln cylinder 1 so that it is spread out over the bottom of the latter for a considerable distance from its upper end. By thus spreading the copperas upon its delivery 15 into the kiln cylinder more efficient action in the burning and incineration thereof is obtained.

The ferric oxide is delivered from the lower end of the kiln cylinder, as indicated at 20 21. The gases of combustion and other gases driven off from the copperas issue from the upper end of the kiln cylinder 1 into a conduit 30 which extends downwardly from the point of delivery of the gases thereinto 25 and joins a horizontal portion 18 having a downwardly inclined bottom, as indicated at 31, and thence upwardly, as indicated at 32, and through a passageway 33 over the upper edge of a wall 34 and thence 30 downwardly into the lower end of a smoke stack 35 or other suitable conduit for carrying away the gases. In order to eliminate from these gases such of them, particularly the sulphuric oxide, as might become injurious if allowed to be discharged into the air the said gases as they travel upwardly at 35 32 are subjected to a washing or scrubbing action. This scrubbing action is effected by the introduction of water from a pipe 35^a 40 on to a screen or perforated sheet 36 of suitable material, such as asbestos, situated above the portion 32 of the conduit or passageway. The water streaming down through these perforations through the gases 45 flowing upwardly through the portion of the conduit at 32 combines with any sulphuric oxide (SO_3) which may be present and removes the same. This water flows from the chamber 31 through a pipe 37 into a well, 50 not shown, and is thereafter caused to flow upwardly through the pipe 35 by means of a steam inspirator, as indicated at 38.

As a result of subjecting the gases to a 55 washing or scrubbing action by the water flowing downwardly through the perforations of the sheet 36 they are rendered heavy so that it is necessary to provide some means to both dry the same and create a draft through the conduit of the smoke stack 35

so as to cause them to flow upwardly therein. This may be effected by the introduction into the said conduit at a point near the bottom thereof of a column of heated air or other gas. I have found that this column of heated air and gases may be supplied from the fire of a stove 40 from which a pipe 41 extends, the upper end of which projects through an opening in the side of a smoke stack 35. The heated air and gases of combustion from the stove 40 enter the 70 smoke stack, heat the inside thereof so as to dry the gases after they have passed through the shower of water from the perforated sheet 36 and cause the same to pass upwardly through the said smoke stack from 75 which they are discharged. The sulphuric oxide having been eliminated from the said gases it is apparent that even though the air may contain large quantities of water vapor no sulphuric acid will be formed and in consequence there can be no injury to objects in the vicinity of the apparatus or plant as heretofore has been the case.

As the gases flow through the conduit 30, 31, 32, etc. to the lower end of the smoke 85 stack 35 the greater proportion of any ferric oxide which may have been carried along therewith is deposited and may be recovered.

The process as above described may be employed also in the treatment of other sulphur compounds, such as iron sulphid, copper sulphid, and copper sulphate.

It will be seen that by my invention I have provided a method and apparatus by the employment of which more efficient and economical incineration of the copperas and other sulphur compounds may be effected and whereby also the greater proportion of ferric oxide which may have been conveyed from the furnace or kiln may be recovered.

Having thus described my invention what I claim and desire to secure by Letters Patent is:

1. The method of manufacturing iron oxide which comprises the delivery of dry copperas with a blast of air into a furnace and thereafter incinerating the said copperas within the said furnace.

2. The method of manufacturing iron oxide which comprises the delivery of dry copperas mixed with a blast of air into the upper end of a rotating furnace and thereafter incinerating the said copperas within the said furnace.

In testimony that I claim the foregoing as my invention, I have hereunto signed my name this 1st day of May, A. D., 1923.

HENRY CARLISLE STEWART.
